CLAIM

The ornamental design for combined food storage container system with food storage containers, as shown and described.

DESCRIPTION

FIG. 1 is a perspective view of a food storage container system of our new design, including a plurality of food containers;

FIG. 2 is a front elevation thereof;

FIG. 3 is a rear elevation thereof;

FIG. 4 is a right side elevation thereof;

FIG. 5 is a left side elevation thereof;

FIG. 6 is a top plan view thereof;

FIG. 7 is a bottom plan view thereof;

FIG. 8 is a perspective view thereof with one of the containers shown separately for clarity of illustration.

FIG. 9 is a front elevation view of FIG. 8.

FIG. 10 is a rear elevation view of FIG. 8.

FIG. 11 is a right side elevation view of FIG. 8.

FIG. 12 is a left side elevation view of FIG. 8.

FIG. 13 is a top plan view of FIG. 8; and,

FIG. 14 is a bottom plan view of FIG. 8.
